UNITED STATES PATENT OFFICE.

DAVID S. JACOBUS, OF JERSEY CITY, NEW JERSEY. ASSIGNOR TO THE BABCOCK & WILCOX COMPANY, OF BAYONNE, NEW JERSEY, A CORPORATION OF NEW JERSEY.

MEANS FOR SUPPORTING AND HOLDING FURNACE-WALLS IN ALINEMENT.

1,315,021.

Specification of Letters Patent.

Patented Sept. 2, 1919.

Application filed October 9, 1917. Serial No. 195,541.

To all whom it may concern:

Be it known that I, DAVID S. JACOBUS, a citizen of the United States, residing at Jersey City, in the county of Hudson, State of New Jersey, have invented certain new and useful Improvements in Means for Supporting and Holding Furnace-Walls in Alinement, of which the following is a specification.

10 In my application, Serial No. 90,058, filed April 10, 1916, I have described a means for supporting the front wall of a boiler setting where the weight of the wall is carried, in part, by struts spaced beneath the wall and 15 at intervals along the front of the stoker so that they do not interfere with the carrying of a uniform bed of fire from side to side of the furnace. In that construction I employ special refractory blocks in the wall which 20 interlock with the tie pieces to maintain the alinement of the wall. In the present invention the arrangement is shown applied to a Stirling boiler with a relatively high wall, requiring the wall to be held by means 25 of two sets of the special refractory blocks arranged so that double lines of the refractory blocks come at two different levels in the wall, whereas in my application Serial No. 90,058 one set only of the special refractory blocks is shown in the front wall; in 30 this respect my previous application being similar to the construction shown in Fig. 2 of the present application. In the present application I have further shown the struts 35 which serve in assisting to support the walls as stepped into nuts at their lower ends, which allows for any necessary adjustment in the length of the struts, whereas this adjustment is not shown in my previous application.

40 My invention relates to means for supporting and holding a furnace wall in proper alinement and will be understood by reference to the accompanying drawings in 45 which Figure 1 is a side view, partly in section, of a portion of a Stirling boiler and the front wall of the setting; Fig. 2 a similar view showing the invention adapted to the setting of a Babcock & Wilcox type of boiler; Fig. 3 a vertical section on the plane of the line 3—3 of Fig. 2; Fig. 4 an enlarged view of a portion of the wall of Fig. 2 with the hopper of the stoker mechanism omitted; Fig. 5 a front view of Fig. 4 with

the outer metallic casing broken away; Fig. 55 6 a view partly in plan and partly in horizontal section of a row of special tiles or blocks with their engaging tie pieces as used in the walls shown in Figs. 1 and 2, the view showing two forms of blocks; Fig. 7 a vertical section, partly in elevation of a modified means for holding the tie pieces; and Fig. 8 a longitudinal section through one of the tie pieces.

Similar reference numerals indicate similar parts in the several views.

Referring to Fig. 1, the numeral 1 designates the front bank of tubes of a Stirling boiler, and 2 and 3 the front steam and water drum and the mud drum, respectively. 70 The boiler is shown as fired by an underfeed stoker, shown diagrammatically in Fig. 1 and more fully in Figs. 3 and 4. This stoker comprises a hopper 4 from which the fuel is fed into the magazines or retorts 5 from which two cylindrical rams 6 and 7 push it into the furnace. Alternating with the retorts are the twyer boxes 8 in each of which a series of twyers 9 is supported. The wall shown in Fig. 1 is without the 80 usual relieving arch and is built up above the stoker ledge plate which plate comprises top plates 10 of the retorts and the top plates 11 of the twyer boxes, the latter resting upon the former. The side walls of the 85 twyer boxes 8, upon which the plates 10 rest, are connected by integral webs 12 which rest upon vertical struts 13. The latter are supported upon beams 14 and thus assist to support the weight of the wall. It 90 is sometimes necessary to remove one or more twyer sections in order to repair the stoker, and to effect the removal of the struts they are shown as threaded at their lower ends and stepped into nuts 15 by which any 95 necessary adjustment in the length of the struts may be made.

The arrangement above described is the same whether the struts are employed to assist in supporting a high wall as shown in 100 Fig. 1, or a low wall, as shown in Fig. 2. In both, the struts are spaced beneath the wall and at intervals along the front of the stoker mechanisms so that they do not interfere with the carrying of a uniform bed of 105 fire from side to side of the furnace.

To maintain the alinement of the front wall, and to prevent movement inward or

outward, I build a part of the wall of one or more horizontal courses of special tiles or refractory blocks and interlock them by means of cast iron tie pieces.

- 5 Referring to Figs. 2, 4, 5, 6 and 8 I preferably lay two courses of the special blocks near the middle height of the wall, the blocks being of either of the forms shown in Fig. 6, that is, they may be like the blocks 10 16 having grooves or recesses 17 in their sides or, as indicated at 18, with a T-groove 19 in the body thereof and opening at the front of the block, such groove being similar to that formed by two contiguous blocks 15 16. The latter are slightly reduced in width at their front ends to accommodate the webs of the tie pieces as clearly shown in Fig. 6. The tie pieces are of general T-shape in section and are formed with a head 20, a web 20 21, and laterally projecting lugs 22 near their front ends, the said lugs and the front web 23 being of greater width than the web 21, as shown in Fig. 4. These tie pieces are preferably of cast iron and are placed in 25 position and the blocks dropped between them, if the latter are of the form shown at 16, so that the heads of the tie pieces will engage the grooves 17 of adjacent blocks, or will engage the groove 19 if the form of 30 block 18 is used. Whatever the form of the block, the projecting lower and upper ends of lugs 22 of the tie pieces engage Z-bars 24 immediately below and above the special blocks. Said bars are rigidly secured, preferably by rivets to the outer metallic casing 25. Brick work immediately below and above the said blocks is formed with an inset, as shown in Fig. 4, so that a space is provided between the front ends of the special blocks and the casing 25 into which 40 space the front portions of the tie pieces extend. This arrangement permits the insertion of the tie pieces and the making of repairs to the wall from inside the furnace and 45 without removing any portion of the casing 25.
- The space provided around the web 21 of the tie pieces, by reducing the width of the blocks 16 at their front portions, as well as 50 the space around the heads 20, is sufficient to permit expansion of the blocks without gripping the tie pieces. Also, as the blocks expand, the tie pieces may slide along the Z-bars 24 and so prevent an undue strain due 55 to the sidewise expansion of the blocks and of the wall as a whole. The expansion of the wall upward cannot cause an undue strain as the blocks will slip up and down over the tie pieces. Any tendency of the 60 wall to lean inward will be resisted by the casing 25 because of the engagement of the

lugs 22 with the Z-bars 24 which latter are rigidly secured to the outer casing. Any outward movement will be resisted by the casing 25.

65

In the structure shown in Fig. 7 the tie pieces are held by two eyebars with no outer wall casing, the said bars serving to prevent the tie pieces and wall from moving inward and at the same time to prevent the wall 70 from moving outward.

What I claim and desire to secure by Letters Patent of the United States is:—

1. A steam boiler furnace having a vertically extending wall with an opening at 75 the bottom thereof, means beneath the wall at the opening to support the wall above the opening, the wall having one or more courses spaced apart, each of the courses having recessed or grooved blocks therein, a fixed 80 member adjacent each of the spaced-apart courses and metallic tie pieces, each engaging the grooves or recesses and one of the fixed members to assist in holding the wall in alinement while allowing relatively free 85 movement thereof in a generally vertical plane.

2. A steam boiler furnace having a vertically extending wall, a plurality of spaced-apart stoking mechanisms beneath the wall 90 and on which the wall rests, the wall having one or more courses spaced apart, each of the courses having recessed or grooved blocks therein, a fixed member adjacent each of the spaced-apart courses and metallic tie pieces, 95 each engaging the grooves or recesses and one of the fixed members to assist in holding the wall in alinement while allowing relatively free movement thereof in a generally vertically plane.

3. A steam boiler furnace having a vertically extending wall, a plurality of spaced-apart stoking mechanisms operating beneath the wall, a plurality of vertical spaced-apart struts assisting to support the wall, the wall 105 having one or more courses spaced apart, each of the courses having recessed or grooved blocks therein, a fixed member adjacent each of the spaced-apart courses and metallic tie pieces, each engaging the grooves 110 or recesses and one of the fixed members to assist in holding the wall in alinement while allowing relatively free movement thereof in a generally vertical plane.

In testimony whereof I have hereunto 115 signed my name in the presence of two subscribing witnesses.

DAVID S. JACOBUS.
